(57) **CLAIM**

The ornamental design for a bicycle saddle, as shown and described.

DESCRIPTION

FIG. 1 is a right perspective view of the bicycle saddle of the present invention;

FIG. 2 is a left perspective view thereof;

FIG. 3 is a rear elevational view thereof;

FIG. 4 is a front elevational view thereof;

FIG. 5 is a top plan view thereof;

FIG. 6 is a bottom plan view thereof;

FIG. 7 is a right-side elevational view thereof; and,

FIG. 8 is a left-side elevational view thereof.

The portions of the bicycle saddle shown in broken lines are for illustrative purposes only and form no part the claimed design.

1 Claim, 6 Drawing Sheets
